UNITED STATES PATENT OFFICE.

JOHN IRWIN BRIGHT, OF VILLA NOVA, PENNSYLVANIA.

SCHOOL BUILDING AND METHOD OF SEATING.

Application filed April 21, 1922. Serial No. 555,837.

To all whom it may concern:

Be it known that I, JOHN IRWIN BRIGHT, a citizen of the United States, residing in Villa Nova, in the county of Delaware and State of Pennsylvania, have invented certain new and useful Improvements in School Buildings and Methods of Seating, whereof the following is a specification, reference being had to the accompanying drawings.

This invention relates to building construction with particular reference to school buildings, and has for an object to provide a building of polygonal configuration and containing compartments or rooms intended for the accommodation of the pupils, and designed particularly to furnish natural lighting in such a manner as to avoid inducing eye strain upon the pupils when their attention is directed to the blackboard or other exhibit placed in the location designed for its reception.

Another object of the invention is to provide a method of seating or arranging the seats and desks of an instruction room constructed in accordance with this invention, so as to place the greatest number of pupils in positions, wherein they face the blackboard or exhibiting surface directly or substantially at right angles to said surface, thereby avoiding wide angles of incidence and reflection between the exhibiting surface, the source of light and the pupils, and thus preventing eye strain which is ordinarily induced when an attempt is made to view an inscription upon some point of a plane surface which happens to coincide with a reflected ray from a source of light.

These and other objects are accomplished primarily by virtue of the present invention, which consists in the provision of a building construction of polygonal conformation defined by two concentric walls to form an annular enclosure which is suitably divided, according to convenience, into compartments or rooms, each of which is defined by walls, one or more of which are angularly disposed relative to one of the light walls at less than ninety degrees. These requirements are met in a room having a floor plan corresponding to a trapezoid, and rooms of this configuration are created

merely by arranging the partitions radially, intersecting the corners of the building.

I have illustrated in the accompanying drawings what I now believe to be the preferred embodiment of my invention, from among other possible forms and arrangements, within the scope of the appended claims, in which drawings:

Fig. I is a view in elevation of a building of polygonal form, constructed in accordance with my invention, the line of vision of the figure being directed at right angles to one of the side faces of the structure.

Fig. II is a view in horizontal section taken through the plane of the first or main floor.

Fig. III is a horizontal section taken through the plane of the second floor.

Fig. IV is a view in transverse, vertical section taken on the line IV—IV of Fig. III.

Fig. V is a view in plan of a room of rectangular form provided with the usual seating arrangement, for the purpose of comparison.

Fig. VI is a similar view of one room of the building shown in the preceding figure, illustrating my improved seating arrangement; and

Fig. VII is a diagrammatic view in plan of a slightly modified seating arrangement embodying my improvements.

With reference to the drawings, 10 and 11 indicate respectively the outer and inner relatively concentric walls of my improved building, forming an annular compartment 12 between them, and a central compartment 13 within the inner wall. These walls define a regular polygon, of any number of sides, but as shown in the drawings, preferably a heptagon or seven sided figure. When planning the main floor, a third wall 14 may be provided, enclosing the inner wall 11 in spaced relation thereto to form an annular corridor 15, suitably perforated to provide points of ingress and egress, so as to avoid the necessity of entering the central compartment 13 when passing from one room to another, while the floor supports of the remaining floors are extended inwardly to form balconies or mezzanine floors 16 overhanging the main floor. Each floor

of the structure is divided into rooms by extending partitions radially across the angular spaces 12. The division is effected preferably by erecting pairs of spaced walls 17 which intersect the corners of the structure and which provide space therebetween for the stairways 18, affording paths of travel between the superposed planes. Other pairs of spaced walls 19 are erected in a similar manner forming spaces 20 therebetween which may be utilized as offices or for other purposes. The introduction of the pairs of partition walls 17 and 19 define rooms 21 therebetween, extending in endless, end to end formation around the angular compartment 12. Owing to the shape of the structure and its manner of subdivision, the rooms 21 are each given a configuration resembling a trapezoid, in which the walls 10 and 11 are parallel, and the walls 17 and 19 are in angular relation, converging toward the center of the structure. These rooms are reserved for instruction or classes, and to that end, a blackboard 22, or other exhibiting plane, is mounted on one of the walls 17 or 19, constituting the front wall of the room. The roof of the central compartment 13 is preferably in the form of a dome 23, constructed of open frame work enclosing glass panels 24 to insure a maximum amount of light, although if desired the central compartment may be left entirely uncovered. The central enclosure may be used for varied purposes, as, for instance, an auditorium, or a gymnasium. The door openings for providing admission to the building are located preferably at the corners between adjacent faces of the outer wall 10, as shown at 25, and hence the said corners are flattened, providing plane surfaces which may be perforated at upper levels to add window openings 26 to others indicated at 27, and placed in the side faces of the outer wall to afford ample light to the instruction rooms. The door openings may, however, be placed at any point on the wall 10. If desired, to provide accommodation for other purposes, certain of the instruction rooms may be subdivided by placing a partition 28 thereacross in a tangential direction to form a trapezoidal room 29 and a room 30 having the form of a parallelogram. Or the partition may be erected in a radial direction, as shown at 31, defining two trapezoidal rooms.

By virtue of the above described construction, many attendant advantages are derived. For instance, the use of corridors is obviated, as it permits the occupants of any floor to pass to the outside of the building through the numerous stair halls without the necessity of passing through any other room. This is an advantage in an emergency as the building can be quickly emptied.

The seating arrangement obviates glare 65 in the eyes.

Every seat has approximately the same visual angle to the exhibition or front wall as has every other seat.

In a modified seating arrangement to be 70 described the distance between a line drawn through the front right hand corner of the desks in one file and a line drawn through the rear left hand corner of the desks in the adjacent file may be also twenty-four inches 75 but the area of the aisle space is substantially greater. The outer wall of each room on the outside perimeter is longer than is the outer wall of any rectangular room of equal area and depth; hence it affords more 80 window space than does the outer wall of any rectangular room of equal area and depth. The four enclosing walls of each instruction room and hall room or stair hall are of necessity bearing walls, and hence 85 each room is a fireproof cell, having direct access to a stairway. This is an advantage that cannot be obtained in a building in which the rooms are rectangular, or placed in continuity or rectilinear relation, except 90 by increasing the area of the plan and therefore the cost of the building. Other advantages will be readily noted by those familiar with the design and construction of buildings.

Not the least important among the many points of merit in the above described form of building construction is the manner in which the shape of the instruction room lends itself to a new and unique arrangement of desks and chairs, whereby the source of natural light is placed in such a manner as to illuminate, to best advantage, the blackboard, etc., without giving rise to annoying reflections or cross rays that would tend to 105 obstruct a clear vision of the exhibits. For the sake of comparison, attention is directed to Fig. V, wherein a conventional form of rectangular room and seating arrangement is shown. The windows 32, it will be seen, 110 pass the light rays into the room in a direction at right angles to the line of vision of the pupils whose gaze is directed toward the blackboard 33. This arrangement permits part of the light rays to pass into the 115 eyes of the students causing unclear vision. As much light enters from the front end of the window direct to the rear of the room as from the rear of the window directed to the front end of the room. Every light ray 120 emanating from a point in a plane in front of a pupil shines to a greater or less degree in his eyes when the line of vision of the pupil, as is normally the case, is parallel to the light wall 10. This glare causes unclear 125 vision and damaging physiological and nervous reactions.

By reference to Fig. VI, showing my im-

proved seating arrangement, it will be seen that the end walls 17 and 19 are disposed at less than a right angle relative to the light wall 10 and the desks 34 are arranged in 5 rows, which may be substantially parallel to the end wall 19, or the wall which carries the blackboard, etc. The side edges of the desks, in each instance, are at right angles to the blackboard, thus causing the pupils when 10 seated behind the desks to partially turn their backs to the light wall 10, or windows 27, from which the light is derived. The aisles, however, run preferably parallel to the light wall, so as to afford a direct 15 passage therethrough from one end of the room to the other. The light rays thus enter the room over the left shoulders of the pupils, and a much clearer vision of the blackboard is possible without attendant eye 20 strain, inevitable in the usual seating arrangement. Also, the relative arrangement of the seats eliminates a file formation and hence the view of each pupil is not obstructed by the placing of one pupil directly 25 in front of another. Attention is directed at this point to the fact that while the floor plan of the structure described in the first part of this specification should be polygonal the merit of the specific trapezoidal 30 shape of the rooms contained therein will decrease as the number of sides of the polygon are increased. This is due to the fact that the walls of the rooms will approach more of a rectangular relation as the number 35 of rooms are increased due to multiplying the number of sides of the polygon. Hence, the preferred floor plan is a seven sided figure, although the number of sides may be increased or decreased without sacrificing the advantages described.

A slightly different arrangement is shown in Fig. VII, wherein the angular relation of the desks to the light wall varies in proportion to their distance from the light wall. 40 The theory of the arrangement can best be explained by reference to the scheme used in planning or laying out a seating arrangement for a specified amount or shape of floor space. The outline of the room is 45 shown as trapezoidal with one wall 19 constituting the front wall of the room to which the attention of the pupils is directed. A base line 35 is drawn parallel to the short side wall 11, and an arc 36 is drawn having 50 its center 36' on and at one end of the base line. This arc is divided into uniform increments, by division points 37, corresponding in number to the number of aisles desired. The distance between the side walls 55 10 and 11 is then divided into the number of files desired, and such points of division indicated by straight lines 38, 39, 40, 41 and 42 drawn parallel to each other and parallel to the said walls 10 and 11. A series of 60 straight lines 43 are now drawn at right 65 angles to the base line 35, but originating at the points 37 of the arc, and intersecting the lines 38, 39, etc., such points of intersection being designated respectively at 38', 39', 40', 41' and 42'. Alternate points of intersection skipping two are now connected by lines to determine the angle which the front edge of the respective desk makes with the said base line 35. Thus, the points 38' and 41' are connected by a straight line, designated 44, 70 and it is the angle of this line that controls the placing of the first desk in the file originating at the point 41'. The front edge of the first desk, designated 41' must coincide with said line 44, and the adjacent side of 75 said desk must coincide with a line 45 drawn at right angles to said line 44. The angle which the front edge of each succeeding desk in the file makes with the base line 35 is determined in the same manner except that the 80 right hand corner of the desk is placed on the lines 38, 39, 40, 41 and 42 at any desired distance below the points 38', 39', 40', 41' and 42' resulting in the assemblage shown in the figure. It will be seen that considering the angular placing of the individual desks, the transverse axis of each desk is respectively tangential relative to an imaginary individual circle (not shown) having its center on the base line coinciding with 85 the center 36', and that the diameters of such circles increase as the desks are placed farther away from said center and the base line. Also, that the points of contact of the transverse axes of the desks with said imaginary 90 circles are displaced angularly on one circle relative to an adjoining circle. This makes a convenient arrangement of desks for the shape of room shown in the figure, bringing the first and succeeding rows of desks substantially but not exactly parallel to the 95 blackboard, causing the desks nearest the windows to be located at a minimum angle thereto, and placing the desks farthest from the windows at a maximum or right angular relation to the light wall. It will be noted that a line parallel to the outside wall and passing through the center of gravity of the seating plan, which seating plan is 100 symmetrically arranged in relation to the outer and inside wall, is substantially nearer the outer wall and the source of light, than in a rectangular room.

Having thus described my invention, I claim:

1. A school building having a floor plan of polygonal outline with a relatively small number of sides defined by a bearing wall, an inner wall in spaced relation thereto and corresponding in outline, and radial dividing 110 members connecting the corners of said walls to form trapezoidal compartments between said members in which the outer wall sides and said members are disposed at acute angles, said dividing members comprising 115 120 125 130

- spaced partition walls to define rectangular compartments therebetween.
2. A school building having a floor plan of polygonal outline with a relatively small number of sides defined by an outer bearing wall, an inner wall in spaced relation thereto and corresponding in outline, partition members connecting the corners of said walls to define class rooms of trapezoidal configuration in which the outer wall and partition members are disposed at acute angles, the wall spaces of the outer wall between said partitions being perforated to provide window openings, exhibiting means located on one of the walls adjacent said perforated outer wall, and an arrangement of desks all of which are directed towards said exhibiting means.
3. In a building structure, a room including a wall having light openings, a wall adjacent said first mentioned wall disposed at an acute angle thereto, and seats arranged to face said last mentioned wall so that the light entering said openings may be directed against the second mentioned wall and originate at points to the rear of the seats to avoid entering the eyes of the occupants of said seats.
4. In a building structure, a room of substantially trapezoidal configuration with the non-parallel walls disposed at acute angles relative to the longest parallel wall, said longest parallel wall having light openings whereby exhibits placed upon an adjacent wall are readily viewed by observants placed directly in front thereof without cross rays of light originating from said window openings entering the eyes of said observants.
5. In a building structure designed for school purposes, a room comprising a long wall, a short wall parallel thereto, and adjacent walls in diverging relation disposed at acute angles relative to the longer wall, said long wall having window openings whereby exhibits placed upon one of the diverging walls may be viewed by observants placed directly in front of said exhibits whereby cross rays of light originating from the window openings are prevented from entering the eyes of the observants.
6. In a building structure designed for school purposes, a room defined by an outer relatively long wall having window openings, a relatively short inner wall parallel and in spaced relation thereto, and diverging walls connecting said outer and inner wall, disposed at an acute angle relative to the outer wall, exhibit means placed on one of the diverging walls, and a plurality of seats and desks arranged in said room so as to be directly opposite the exhibits.
7. In a building structure designed for school purposes, a room defined by an outer relatively long wall having window openings, a short wall parallel and in spaced relation thereto, diverging walls connecting first mentioned walls, exhibiting means placed on one of said diverging walls and a plurality of desks arranged in said room in rows, each row being parallel to the exhibit bearing walls, and said desks arranged in spaced relation to form aisles parallel to the light bearing wall.
8. A building having a floor plan of polygonal outline defined by an outer bearing wall having flat sides, the corners of said wall being flattened and containing door and window openings, an inner wall in spaced relation thereto of corresponding outline, the faces of which are parallel to the faces of the outer wall, a plurality of radially extending means to define compartments, and connecting the corners of said walls, each means comprising a pair of spaced partitions defining rectangular compartments therebetween coinciding with the door openings to form halls for stairways and coinciding with the window openings to form rooms.
9. In a building designed for school purposes, a room defined by an outer wall having light openings, an inner wall parallel thereto and diverging walls connecting the first mentioned walls, an exhibiting means placed on one of said diverging walls, and a plurality of seats arranged in said room, all of which face the exhibit bearing wall, said seats adjacent the light bearing wall bearing an angular relation thereto lesser than those seats more remote from said wall.
10. In a building structure for school purposes, a room defined by an outer wall having window openings, an inner wall parallel thereto, and diverging walls connecting the first mentioned walls, and exhibiting means placed on one of said diverging walls and a plurality of desks and associated seats arranged in said room, the desks located adjacent the second mentioned wall being arranged in file substantially parallel thereto, and the desks arranged near the first mentioned wall being arranged in file, each desk of said file being disposed at an angular relation to said wall of less than ninety degrees and the remaining desks between said files being arranged at angles varying therebetween.
11. A building having a polygonal floor plan and partition walls defining trapezoidal configured rooms, one of said walls being adapted as a point of exhibition, a source of natural light remote therefrom, and seats arranged to face the point of exhibition, said seats adjacent the source of light being arranged at an acute angle thereto, and the angular disposition of the other seats increasing as their location recedes from the source of light.
12. A building having a polygonal floor plan and partitions defining substantially

trapezoidal configured rooms, one wall in each room being adapted as a point of exhibition, a source of natural light in an adjoining wall, and seats arranged to face the point of exhibition; said seats adjacent the source of light being arranged at an acute angle relative thereto, the seats remote therefrom at substantially right angles thereto, and the intervening seats at angles varying

between the relative angles of the first mentioned two series of seats. 10

In testimony whereof, I have hereunto signed my name at Philadelphia, Pennsylvania, this 18th day of April, 1922.

JOHN IRWIN BRIGHT.
